UNITED STATES PATENT OFFICE.

WILHELMUS KOOT, OF UTRECHT, NETHERLANDS.

SAFETY LOCKING DEVICE.

Application filed August 11, 1921. Serial No. 491,360.

To all whom it may concern:

Be it known that I, WILHELMUS Koot, metal worker, subject of the Queen of the Netherlands, residing at Utrecht, in the Kingdom of the Netherlands, Trompstraat 34 B, have invented certain new and useful Improvements in Safety Locking Devices, for which I have filed applications in Germany, filed February 19th, 1920, No. K. 10 72127, granted January 2nd, 1922, under No. 353,703; England, filed June 21st, 1921, under No. 16963; France, filed July 13th, 1921, under No. 147,091, granted March 15th, 1922, under No. 538,209; Belgium, filed July 1st, 1921, under No. 237,717, and of which the following is a specification.

This invention relates to safety locks for the doors of houses, safes, for locking chests and travelling trunks and for other purposes.

According to this invention it is only possible to open the door or chest when a pin is inserted through a number of apertures formed at the same angle of inclination with a series of other openings which are distributed over two or more concentric cylinders, and which latter can be turned one in another and within the actual casing of the lock.

For this object the actual safety arrangement of the lock consists of a plurality of cylinders concentrically arranged one in another on the periphery of which a series of perforations are formed which run radially towards the common central axis of all the concentric cylinders. Accordingly all the perforations of each cylinder lie in planes, which are different but stand vertically to the common central axis of all the cylinders.

These perforations formed in the separate cylinders, may either be carried right through the separate cylinders in such a way that an inserted pin can be passed through each of these perforations radially to the central axis; or they may be formed in such a way that they are only dummy perforations which do not entirely pass through the cylinder walls; all these radial perforations do not take part in the actual operation of locking and opening.

These radial apertures are actually only means for increasing the safety of the lock by rendering the unauthorized opening more

difficult by misleading the person attempting it when inserting the pin in the lock.

The actual members by means of which the lock can be opened, form channels or perforations which are formed in the concentric cylinders and carried entirely through them. Each of these perforations is in a plane which lies parallel with the axis of the cylinder. Each cylinder has only one perforation which shares in the opening of the lock and which lies in the said plane.

The opening of the lock can be operated only when the last mentioned perforations coincide or are adjusted in a straight line. For opening the lock, the presence of two further perforations is however necessary which must fall into line with the above mentioned actual opening passages in the position which is ready for opening. Of these two perforations one is located in the front wall of the case and the other on the opposite side of the inner wall.

When the actual opening passages bored through the cylinders are adjusted in one line and this line also coincides with the two apertures formed in the case, the opening of the lock by means of the insertion pin mentioned, can take place.

The adjustment into the position ready for opening is effected by turning the separate cylinders into the position which is only known to an initiated person. For this object the inner cylinder is provided with a rotary arm, whilst the other cylinders each have a pin, on which the said arm rests and whereby the separate rotation of each cylinder or simultaneous rotation of all the cylinders is rendered possible.

By being turned the separate cylinders are then each brought into the position in which the said perforations form a continuous line. For this object on the side of the casing, on which the rotary arm rotates, marks for instance, figures or letters or recesses are provided and to each cylinder there corresponds a mark or number which, as regards this respective cylinder, indicates the end position into which the corresponding cylinder must be adjusted in order to assume the position when the lock is ready for opening.

To each cylinder one such mark is provided.

In the same line in which all the perforations or passages and the perforations in the lock casing coincide for the case of the position ready for opening of the lock, there is 5 also a locking bar. When the safety lock is adjusted, this locking bar lies within the lock casing. In the position in which the lock is ready for opening, however it can be pushed forward by the inserted pin, when 10 it emerges from the casing and lifts the lock latch out of the hook on which this latch rests.

The number of the concentric cylinders may be any suitable one. The safety of the 15 lock against unauthorized opening increases with the number. The number of the positions which the cylinders can assume, that is to say, the combination possibilities for safety against unauthorized opening may be 20 calculated by the following formula: a^n in which a is the number of the marks or signs and n the number of the concentric cylinders.

The construction may also be carried out 25 in such a way that the movement of the insertion pin is not operated by hand but mechanically by turning a suitable rackgear, the pin itself being partially formed as a toothed rod or rack.

Now referring to the accompanying drawings, the invention is illustrated in two examples of construction, in which Figs. 1-4 show one form of construction in which the movement of the insertion pin is effected 35 by hand, and Figs. 5, 6 and 7 an arrangement for mechanically operating the insertion pin.

Fig. 1 is a plan view.

Fig. 2 a longitudinal section.

Fig. 3 a horizontal section on the longitudinal axis of the lock.

Fig. 4 is the insertion pin serving for opening the lock.

Fig. 5 is a vertical section of a mechanical means for adjusting the insertion pin.

Fig. 6 is a view of the device from above.

Fig. 7 a view of the previously mentioned concentric cylinders with the perforations for the passage of the insertion pin.

1 is the casing of the lock, 2, 3 and 4 are concentric rings or cylinders, the number of which, in the example illustrated in the drawing, is assumed to be three; 5 are dummy perforations formed in the cylinders which run radially to the central axis. These 55 dummy perforations may be made as desired, either only in the outer cylinder, and therefore do not require to be carried through the entire cylinder wall, or in case these dummy perforations are carried 60 through the outermost cylinder 4, in order to increase the deception against attempts at unauthorized opening, the middle, or even the innermost cylinder may be provided with 65 perforations or passages running entirely through the cylinder walls or only partially

bored through, that is to say, vacant passages.

These dummy openings 5 need not share in the opening of the lock, even when all the three cylinders are to be provided with 70 completely continuous perforations and when all the perforations of the cylinders are adjusted in one line and they cannot take part in the opening of the lock in consequence of their radial position. 75

The actual opening passages are indicated by 6, which run through all the cylinders but are not carried in them any longer radially to the central axis but lie in a plane which is parallel with the central axis of 80 the cylinders. 7 are perforations arranged in the front and rear part of the casing which form in common with the perforations 6 the opening channel or passage. 85

8 is the locking bar which is arranged in the chamber 9 of the casing, and which is under the action of a spring 10 which tends to return the bar 8 always towards the interior of the chamber 9 and to hold the same 90 therein. 11 is the closing plate of the lock, 12 the hook in which the door latch lies. 13 are the marks to which the separate cylinders are adjusted, and 14 is the rotary arm about which the cylinders 2, 3, 4, are turned 95 by means of the pins 15, 16 and brought into the position ready for opening. The rotary arm 14 may be turned up about its axis of rotation 17 so that the pins 15, 16 according to the positions of the cylinders can be located on any side of the arm. 100

The action of the lock when moved by hand, is as follows:—

By turning the arm 14, which thereby bears on the pins 15 and 16, the cylinders 3 and 4 and also the cylinder 2 can be brought 105 into the position ready for opening, which is indicated for each separate cylinder by a given mark 13 and in which the perforations 6 are adjusted in one line with the perforations 7. 110

By inserting the pin 18 through these perforations 6 and 7, the rod 8 is pushed through the locking plate 11, whereby the door latch is lifted and the opening of the door is possible. 115

In the form of construction illustrated in Figs. 5, 6 and 7 with mechanical means for operating the insertion pin, 1 indicates the lock plate and 2, 3, 4 and 19 are the concentric cylinders. 18 indicates the insertion pin, which however, in this case is not loose but is compulsorily guided. 120

The compulsory guidance is effected by the pin 18 being formed as a rack bar 20 at its end which is away from the cylinders and the teeth of this rack bar mesh with a suitable gear wheel 21. 125

The adjustment of the gear wheel 21 is effected by means of a turn button 22. The cylinders are provided in the manner herein- 130

before described with perforations or passages which extend right through or are only partially perforated, that is to say, which are blanks.

- 5 In Figs. 5 and 6, 23 shows a plate, on which the concentric cylinders rest; this plate is provided with teeth 24 with which the beak 27 of a pawl 25 which is under the action of a spring 26 meshes or gears.
- 10 The object of this arrangement (23, 24, 25, 26, 27) is merely to be able to ascertain by audible signals how frequently each separate concentric cylinder is turned in order to facilitate for the expert the opening of the lock. At each rotation the pawl 25 engages by its projection 27 in one of the recesses 24 and gives an audible signal. The number of these audible signals enables a check to be made as regards the number of revolutions executed by the separate cylinders.

What I claim as my invention and desire to secure by Letters Patent of the United States is:—

1. A permutation lock having a plurality 25 of rotatable concentric cylinders having a plurality of radial dummy perforations therein and extending only partially therethrough, each of said cylinders having a perforation extending entirely therethrough, said last named perforations angularly inclined to the radial perforations and adapted to be brought into alignment in a common plane.
2. A permutation lock having an outer casing, a plurality of rotatable concentric cylinders within said outer casing, and having a plurality of dummy radial perforations therein and extending only partially therethrough, each of said cylinders having a perforation extending entirely therethrough, said last named perforations angularly inclined to the radial perforations and adapted to be brought into alignment in a common plane offset to the axis of the cylinders.
- 45 3. A permutation lock having an outer casing, a plurality of rotatable concentric cylinders within said outer casing, and having a plurality of dummy radial perforations therein and extending only partially therethrough, each of said cylinders having a perforation extending entirely therethrough, said last named perforations angularly inclined to the radial perforations and adapted to be brought into alignment in a common plane offset to the axis of the cylinders.
- 50 4. A permutation lock having an outer casing, a plurality of rotatable concentric cylinders within said outer casing, and having a plurality of dummy radial perforations therein and extending only partially therethrough, each of said cylinders having a perforation extending entirely therethrough, said last named perforations angularly inclined to the radial perforations and adapted to be brought into alignment in a common plane offset to the axis of the cylinders.

cylinders and said casing provided with a plurality of perforations only one of which lies in the said common plane.

4. A permutation lock having an outer casing, a plurality of rotatable concentric cylinders within said outer casing, and having a plurality of dummy radial perforations therein, each of said cylinders having a perforation therethrough, said last named perforations angularly inclined to the radial perforations and adapted to be brought into alignment in a common plane offset to the axis of the cylinders, said casing provided with a plurality of perforations only one of which lies in the said common plane and said casing provided with a chamber, a spring pressed bar in said chamber and a pin adapted to pass through said last named perforations when aligned and to engage said bar.

5. A permutation lock having an outer casing, a plurality of rotatable concentric cylinders within said outer casing, and having a plurality of dummy radial perforations therein, each of said cylinders having a perforation therethrough, said last named perforations angularly inclined to the radial perforations and adapted to be brought into alignment in a common plane offset to the axis of the cylinders and said casing provided with a plurality of perforations only one of which lies in the said common plane and said casing provided with a chamber, and a pin adapted to pass through said last named perforations when aligned and to engage said bar and means to actuate said pin.

6. A permutation lock having an outer casing, a plurality of rotatable concentric cylinders within said casing having a plurality of radial dummy perforations therein in each of said cylinders having a perforation therethrough, said last named perforations angularly inclined to the radial perforations and adapted to be brought into alignment in a common plane offset to the axis of said cylinders and said casing provided with a spring pressed pawl adapted to enter said last named perforations to audibly indicate the rotation of said cylinders.

In testimony whereof he affixes his signature in presence of two witnesses.
